WRITING INSTRUMENT

Raymond A. Lanoie, East Greenwich, R.I., assignor to
Garland Industries, Inc.

Filed Apr. 17, 1972, Ser. No. 245,005

Term of patent 14 years

Int. Cl. D19—06

U.S. Cl. D74—17 B

FIG. 1

FIG. 2

FIG. 3

FIG. 4

FIG. 1 is a perspective view of a writing instrument showing my new design;

FIG. 2 is a top plan view thereof;

FIG. 3 is a fragmentary side elevational view thereof, on an enlarged scale; and

FIG. 4 is a section taken on line 4—4 of FIG. 3.

The essential features of the present design resides in the divergent configuration of the top of the instrument, with a flat-topped faceted portion extending around the periphery of the instrument at the top end thereof and extending downwardly for slightly more than one-half of said divergent area, said flat top having a centrally positioned rounded dome.

I claim:

The ornamental design for a writing instrument, substantially as shown and described.
